[57] CLAIM

The ornamental design for a fence panel, as shown and described.

DESCRIPTION

FIG. 1 is a perspective view of the fence panel embodying the design of the present invention;

FIG. 2 is an end elevational view thereof, the end opposite being a mirror image of the end shown in FIG. 2; FIG. 3 is a front elevational view thereof, the rear being a mirror image of the front shown in FIG. 3; and, FIG. 4 is a top plan view thereof, the bottom view being a mirror image of the top view shown in FIG. 4.

FIG. 1

FIG. 2

FIG. 4

FIG. 3
